Primary Examiner—B. J. Bullock
Attorney, Agent, or Firm—Alan Kamrath[57] **CLAIM**

The ornamental design for a handle receiving frame for a suitcase, as shown and described.

DESCRIPTION

FIG. 1 is a front-left-top perspective view of a handle receiving frame for a suitcase, showing my new design; FIG. 2 is a reduced front elevational view thereof; FIG. 3 is a reduced rear elevational view thereof; FIG. 4 is a reduced left elevational view thereof; FIG. 5 is a reduced right elevational view thereof; FIG. 6 is a reduced top plan view thereof; FIG. 7 is a reduced bottom plan view thereof; and, FIG. 8 is a reduced rear-left-top perspective view of a handle receiving frame for a suitcase of my new design, a handle and tubular members being shown in broken lines for illustrative purposes only and forming no part of the claimed design.
